UNITED STATES PATENT OFFICE.

JOSEPH P. BEM, OF FRESNO, CALIFORNIA, ASSIGNOR TO PACIFIC PITTING MACHINE COMPANY INC., OF FRESNO, CALIFORNIA, A CORPORATION OF CALIFORNIA.

PEACH-PITTING MACHINE.

Application filed May 9, 1924. Serial No. 712,060.

To all whom it may concern:

Be it known that I, JOSEPH P. BEM, a citizen of the United States, residing at Fresno, in the county of Fresno and State 5 of California, have invented new and useful Improvements in a Peach-Pitting Machine, of which the following is a specification and which is illustrated in the accompanying drawings.

10 This invention relates to peach-pitting machines in general, but particularly to a certain machine described in my United States joint patent on a "Peach pitter" issued Jan. 15, 1924.

15 The principal object of my present invention is to effect a better operation of the machine as a whole, with a resulting more perfect product.

This is accomplished severally through 20 improved locating means allowing better for inequalities at the stem end of the fruit, a better method of removing the locating devices preparatory to bisecting the peach without displacing it, a positive actuation of 25 the impaling arms, more permanent impaling needles, improved gripping means during the pitting period preventing the fruit from slipping, improved drive to the bisecting device, improved operation of the 30 pitting blades, means controlled by the operation of the machine or the fruit for recording the output, and improved general clutch control, as well as other improvements to the mechanism contributing to the more permanent co-operation of its functioning parts.

I attain my objective outlined above, by the construction shown in the drawings hereto and in which:—

40 Figure 1 is a perspective view of my complete machine with part of the protective casing removed from the frame to reveal the mechanism. Figure 2 is a side view of the machine, and Figure 3 is a rear view thereof.

45 Figure 4 is an enlarged view, looking down at an angle, of one set of the several sets of peach centering and peach gripping devices which project from the carrier, and shows a peach dotted in position. The view

is taken from the open side of the carrier opposite the side shown in Figure 2.

50 Figures 5 and 6 show, somewhat more enlarged, progressive removal of the fruit centering devices. Figure 7 shows in similar enlargement to Figure 4 the relation of the various devices to half peaches at a point between the pitting table and point of discharge of the pitted halves of the fruit.

55 Figure 8 is an approximately full size side elevation of one of the oscillating pitting blades. Figure 9 is a cross section of Figure 8 taken along the line 9—9 thereof, and Figure 10 is a diagrammatic representation showing the angular position of the blade in entering and leaving a half peach in cutting around the half pit.

60 Figure 11 is a detail sketch of the linkage for operating the impaling pins. Figure 12 is an enlarged cross section of the shell form impaling pins.

65 Figure 13 is an enlarged detail of the intermittent locking mechanism for the carrier.

70 Figure 14 is an enlarged detail showing the operation of the resilient bloom end seat.

75 Before taking up a detailed description of the drawings it might be stated that since the general functioning of this improved machine is similar in most respects to my former joint patented machine alluded to, this specification will be shortened by referring to said other patent for a general description of the operation of the machine, and will only deal with the improved construction realizing the improvements above enumerated.

80 In the drawings a frame 1 supports the various elements and is normally covered over with any suitable covering to enclose the mechanism and is provided with a suitable opening for insertion of the fruit, also openings for discharge of the fruit and pits.

85 A revolving carrier is shown at 2 supported on a stationary shaft 17 and carrying several sets of fruit receiving devices, 4 and 5, fruit inhaling devices 6, and clamping devices 7.

The set of devices at "A" in Figure 1 is in the peach receiving position, or point of rotation of the carrier at which the operator inserts the fruit.

5 The carrier is intermittently actuated by a suitably wired and conveniently switched motor 8 through suitable mechanical transmission mechanism, and it travels in the direction of the arrow to pass the fruit over 10 the saw 9 for bisecting it then to present it over the pitting tables 10 all as described in the former patent mentioned.

Figure 4 shows in larger representation 15 the position of one set of fruit receiving and associated elements at the fruit receiving position with a peach dotted in place. At 4 is shown the resiliently mounted ring-shaped seat or cup for receiving the bloom end or tip of the peach, and at 5 is the stem end 20 locating device which latter is a hollow socket or open ended tube transversely slotted at 11 to provide for easy release of, or scraper to discharge any, broken piece of stem which might have lodged within the 25 device. The device is thus made hollow so that it will straddle any small piece of stem as frequently left on a peach and center the peach by seating itself in the depression around the stem.

30 The stem end locating device is carried by an arm 12 and is adjustable therein by being threaded thereto and with a clamp nut at 13, for accurately positioning it over the center of member 4 and it is also adjustable axially 35 of member 4 by the threaded extension 14 as formerly.

The arm 12 is pivotally and slidably supported between two standards 15 so that it 40 can be first lifted to clear the peach and then swung in the plane of the revolution of the carrier to withdraw it for clearing the saw after the peach has been centered from opposite sides of the pit in the impaling devices 6.

45 The operation of the various devices projecting from the carrier is effected as previously through stationary cams 16 attached to the fixed shaft 17 on which the carrier revolves. The cams are double acting, i. e. 50 have an undulating groove around one side of a disk, and at one portion of each disk is an opening through the outer rim for insertion of the cam rollers secured to the various sliding arms. The openings are 55 shown in Figure 4 where these features are visible through the open side of the carrier.

The cam rollers are all revolvably carried at the inner ends of a plurality of sliding arms or rods for actuating the various centering and clamping devices. The rods slide 60 radially in fixed tubes or spaced bearings secured to the carrier.

In Figure 4 the sliding rod which operates 65 the arm 12 is shown at 18 and its cam wheel at 19. This particular rod has a toothed

rack 20 in one side meshing with a gear 21 pivoted to a bracket 22 secured to the outside of the carrier and is arranged to revolve the gear back and forth as the rod is moved axially in its supporting tube 23 by the cam. 70 The gear 21 carries a crank arm 24 to which is pivoted a rod 25, in turn pivoted to the end of the arm 12 between the standards 15.

The arm 12 is slotted at 26 and pivoted through this slot to the standards by the pin 75 27 in such a manner that it will swing to the right (Fig. 5) when the gear 21 is revolved to the right. But in order to make the device 5 first lift clear of the peach before swinging the arm 12 the latter is restrained 80 from swinging by guides 28, 29 on the standards, and which force the arm 12 to first slide bodily outward beyond the ends of the guides and to the end of its slot 26, after which it pivots at the end of the slot and swings to the right and continues until it reaches the position shown in Figure 6. The inner guides 29 are bent away from the standards as shown at 30 to guide the pivoted end of the arm 12 upon return movement. 90 When the arm 12 is in receiving position as shown in Figure 4 it is locked rigidly between the guides 28 and 29 and seated at the upper end of the slot 26 against the pin 27.

95 The bloom end seat 4 is surrounded by a circular casing slidably supported on two rods 32, 33. These rods telescope within guiding tubes 34, 35, one of which conceals a suitable spring 36 for resiliently urging the seat outward a limited distance, and the seat is bodily pulled inwardly to clear the saw by means of an extension from the telescopic tube 35 directed through the bearing block 37 and having a cam roller against one of the cams 16 in a manner similar to all the other sliding rods. 100

105 Figure 14 shows the internal arrangement of the sliding bloom seat support, and at 116 is shown a gravity hook which falls during the rotation of the carrier and holds the seat in withdrawn position until a peach is pressed against the seat and upon which the hook drops to permit the seat to come out to fit the peach whether it is large or small. During the sawing and pitting operations the seat is of course withdrawn inwardly by the main cam 16 acting on the cam roller 117. 110

115 The tip cutting knife 38 projects through the edge of the circular casing and is connected to a telescopic rod 39 pivoted at both ends and which rod is struck by the knob 40 upon inward movement of the pivoted impaling arms 41.

120 The impaling arms 41 carry the impaling devices or pins 6 and are both connected by links 42 for positive co-operative movement toward and from the peach to a minimum distance slightly less than the smallest 125 pit thickness. The links are all pivoted to

a sliding rod 43 actuated in and out by the main cam as described for the other rods. This rod is telescopic and has a spring interposed as sketched in Figure 11 so that although the rod is moved positively in and out by the cam it will yield on the outward movement which draws the impaling arms together so that the impaling pins 6 will stop when they strike the opposite sides of the pit yet securely grip it to carry the peach over the saw 9 for bisecting it.

The impaling pins 6 instead of being solid as formerly, are of channel or U section as indicated in the enlarged diagram in Figure 12, and the pins travel to carry the fruit in the direction indicated. I use this hollow shell form of pin as the hole made by it in the fruit closes up readily after withdrawal, a great advantage over the round pin, but of course other shell forms such as a V or X may also be used to gain this end.

Having found it difficult to maintain the alignment of the wire pins formerly used I now form the pins in pairs as shown, having a large connecting web of metal 6' which stiffens them and affords a firm bolting support to the arms 41. The web 6' is slotted for adjustment on the clamping bolts 44.

Straddling each impaling arm 41 and loosely pivoted over the arm shafts 45 are clamping arms 46 each having an extension 47 hooked to a small spring 48 to hold them open as far as the position of the impaling arms will permit.

The clamping arms all carry two rubber bands 49 tensioned and hooked over small arms 50. The bands have a loop at each end and are so made by proper incorporating of textile material that they have practically no stretch for half their length "B" but are more elastic along the half "C" (see Figure 4). The bands have a ribbed surface as indicated and their object is to serve as yielding clamps for clamping the half peaches against the pitting tables, and the varying elasticity of the bands is for the purpose of holding the fruit by a relatively unstretchable portion so that the fruit will not be liable to "crawl" out of position during the action of the pitting knives.

The clamping arms 46 are not operated by the main cams as are the other devices, but are forced against the half peaches when same are over the pitting tables by oscillating shafts 52 actuated at the proper time by one edge of double cams 53 attached to disk 53' mounted at the base of the machine on the clutch shaft 64. The shafts 52 are vertically arranged at both sides of the machine and bevel geared at their lower ends to a common transverse shaft 54 and which latter shaft is rocked by a cam rod 55 having a roller bearing against the cam 53, the rod being pulled toward the cam by a powerful spring 56 (see Figure 1).

At the upper ends of the shafts 52 are curved arms 57 adapted to strike the clamping arms and move them inwardly so that the bands 49 will remove the pitted fruit from the impaling pins to the chute 58, and at the same time the shafts function to clamp the halves of the next peach over the pitting tables by operating a pivoted arm 59 through pulling of a spring 59', the arm carrying a roller 60 which strikes the outer edges of the clamping arms 46 moving them inwards and forcing the bands 49 tightly though resiliently against the peach halves. Thus the movement of the shafts 52 clamps two peach halves against the tables for pitting, and at the same time discharges two already pitted halves after having passed the tables.

The shafts 52 only operate during the stationary periods of the carrier 2 and which latter is intermittently operated by a rod 61 pivoted at the lower end to the side of the disk 53' and having at its upper end a suitable pawl engaging ratchet teeth 62 adjustably mounted on the rim of the shell 62' functioning substantially as described in the former patent, but the interlocking of the carrier is effected by the shaft 52 which carries an arm with a pair of small rollers which intermittently engage opposite sides of the adjustably mounted locking brackets 76. The brackets are bolted to the carrier through slots for adjustment to determine the exact locking positions, and one of the little rollers is resiliently mounted so as to force the bracket tightly against the rigid one. These rollers are numbered 77, the arm 78, and are hidden by the frame of the machine in the general views, tho their operation is indicated in Figure 13.

The cams 53 have faces or working edges for operating the shaft 52 and the pitting knife shafts 63 in their proper sequence and are loosely mounted on a shaft 64 carrying half of a foot operated clutch 65. The other half of the clutch 65 is carried on a gear reduction shaft from the gear reduction in the box 66.

The reduction gears within the box are driven from a pulley 67 on the outside of the box belted to the motor 8 by a belt 67'. The motor also carries a double or two pulleys 68 having two duplicate belts 69 driving the circular saw 9 over two similar pulleys (not visible in the drawings) mounted side by side on the saw shaft 70.

At the sides of the saw are sponges or other resilient capillary devices 71 positioned in a tank 72 at the lower part of the saw and which tank contains water below the saw into which the sponges dip for supplying moisture to the saw sides, very necessary in order to prevent the accumulation on the saw of a cementitious material composed of fruit juices and pit saw dust. The tank has

a spray guard 73 extending partly over the saw, and by reason of the main cam action on the impaling arms the peach halves as soon as sawed are lifted over this guard on 5 their way to the pitting tables.

The clutch 65 controls the entire operation of the machine with the exception of the saw which runs continuously when the power is switched on. The clutch is similar to any punch press clutch and is tripped by a foot lever 74 which is depressed by the toe of the operator's foot while co-operating 10 with a fixed foot rest 75.

Upon depressing the lever 74 the clutch is 15 at once tripped into engagement by the usual type of mechanism which need not be described specifically, and whereupon the disk 53' revolves to intermittently revolve the carrier 2, and the cams 53 through cam 20 rod 55 intermittently operates the fruit clamping and discharging shafts 52, and through a similar cam rod 87 operates the pitting knife shafts 63 to swing the arched blades through the half peaches in a manner 25 substantially as described in the prior patent mentioned, but with the differences hereafter noted.

The blades themselves have been changed in form as shown best in Figure 8 at 79 and 30 are also kept in constant circumferential oscillation while being swung through the peach halves.

This is accomplished by having the shafts 35 small shafts 80 which are run continuously from the motor 8 from a small pulley 81 by means of a belt 82 to pulley 83 on a counter-shaft 84 which is bevel geared through two small transverse shafts concealed by a supporting bracket 85 to the small bevel gears 40 86 secured to the lower ends of the blade oscillating shafts 80 and positioned just above the rock shaft 88 which carries the bevel gears 89 which mesh with corresponding bevel gears 90 on the lower ends of hollow shafts 63 and positioned just above the small gears 86.

The rock shaft 88 is rocked by the arm 91 through the link 92 which connects with an 50 arm 93 to the jack rock shaft 94 which is rocked by the cam rod 87. It should be here noted that the cam rod 87 upon actuation by cam 53 does not force the arched blades through the fruit, (as with the former machine) but only returns the blades to starting position, as the blades are both resiliently pulled through the fruit by the cam returning or pull back spring 95 upon falling away of the cam surface in revolving.

60 Thus the blades are adapted to stop in case anything goes wrong, such as an unusual pit stopping the blade in either half peach.

In case no peach was in pitting position 65 the blades would find no resistance, and

therefore an air cylinder 96 is connected to the rod 87 to prevent it from too sudden a return.

In case the knives should return very slowly through the peach halves on account of a very hard cut, or should stick, it is evident that no further action of the machine should take place or the knives would be destroyed. This is automatically cared for by connecting a rod 97 to an arm 98 from the jack rock shaft 94 which moves back and forth with the rocking of the shafts and swinging of the knives. This rod 97 carries a suitable trip lock 98 which only frees the foot lever 74 for descent upon the completion of the cutting stroke each time and consequent return of the rod 97, thereby preventing the clutch from being tripped except at such times as the knives have cleared the peach and all is safe for the next movement of the carrier. If nothing interrupts the action of the knives the foot on the clutch lever rises and falls with each intermittent movement of the carrier, but the foot cannot fall for the next tripping action until the knife travel is fully completed.

The oscillating blades and associated parts are shown in Figures 8 and 9. Each shaft 63 has an offset portion 99 on which the carriage 100 for the blade 79 is mounted. The carriage is itself mounted on a carrier 101 slideable perpendicularly with respect to the offset shaft 99 on guide pins 102. The carriage is pivoted to the carrier at 109 for general rocking motion and is stabilized by two concealed springs 103, and the blade 79 is a slightly elongated arch secured at both ends to a rocking bar 104 pivoted transversely to the carriage at 105.

Within an opening in the carriage is a revolving face cam wheel 106 mounted on a small shaft 107 revolved by a universal and sliding joint connection 108 to internal shaft 80 passing through the shaft 63 as explained.

The revolving cam 106 engages a seat 109' in the under side of the rocking bar 104 so that the bar is constantly rocked at high speed as the cam revolves to produce a circumferentially oscillating or sawing motion to the cutting edge of the blade, tho no teeth are used on the blade. The blade swings on an arc through the half peach upon rocking the offset shaft 63 a half turn, and is free to rise and fall on the pins 102 for adjusting itself to the pit, being normally held down by the spring 110 bearing against the pin 109 at one side of the carriage, and is also free to rock on pin 109 for general displacement to accommodate itself to the pit, without in any way interfering with the constant rotation of the cam.

While I show a cam for oscillating the blade on its rocking bar it is evident that

other arrangements may be used to accomplish the same result.

The pitting blade is set to enter the stem end of the peach through the pitting tables 5 and just beyond the end of the pit as determined by the locating device 5 as in the former machine, but is preferably arranged as shown in Figure 10 to enter at one angle as shown at "X" and gradually change to 10 "Y" and "Z" on its way out of the peach half. This is accomplished by placing the axis of swinging rotation at "W" relatively nearer to the point "X" of entry than to the point "Z" of exit and forcing the carriage 15 to rise as the blade advances. This produces a hugging action to the blade in rounding the pit curve and prevents it from flying out tangentially.

The peaches are automatically tallied by 20 contact with a pivoted lever 111 arranged centrally so that it will pass between the impaling pins 6 when no peach is carried, but will be tripped by each peach passing. Figure 2 shows the arrangement, the lever 111 is supported on a suitable bracket 112 and 25 connects to a wire 113 passing through a tube 114 to operate a pull actuated counter suitably arranged at 115. The wire and lever are returned to position each time by 30 a suitable spring 116.

Referring to the appended claims I wish 35 it to be understood that since my machine is primarily designed for bisecting and pitting peaches, will also perform similarly on other fruit within its capacity, and in the case of pears, apples and the like, will cut out the core of the halved fruit, therefore when I use the word "peach", "pit" or 40 "pitting" in the claims it is with the intention that such words include any such fruit and "core" or "coring" as well, to cover such usage.

I claim:

1. In a peach pitting machine of the character described, an arched blade mounted for travel in an arcuate path on an axis substantially parallel to the plane of the arch and adapted to cut out the half pit of a half peach presented thereto, means for presenting a half peach thereto, means for swinging the blade on its mounting through the fruit, and means for continuously oscillating the blade circumferentially while cutting the fruit.

2. In a peach pitting machine of the character described, means for pitting a half peach including an arched blade adapted for passing through the half peach around the half pit thereof, means for supporting a half peach in cutting relation to the blade, said blade being pivotally mounted to swing through the half peach from a point nearer to its point of entry than to its point of emergence.

3. In a peach pitting machine of the char-

acter described, means for pitting a half peach including an arched blade adapted for passing through the half peach around the half pit thereof, means for supporting a half peach in cutting relation to the blade, 70 said blade being pivotally mounted to swing through the half peach from a point nearer to its point of entry than to its point of emergence, and the blade being of a flattened section resiliently mounted with reference 75 to its pivotal point to diverge slightly from the pit in ascending the curve thereof upon entering the fruit and gradually converge toward the pit in descending the curve beyond the crown thereof.

4. In a peach pitting machine, an arched blade, means for moving the blade in an arc around a half pit in a bisected peach, and means for oscillating the blade during its movement around the pit.

5. In a peach pitting machine, a rock shaft having an offset, an oscillating frame mounted on the offset, and an arched blade mounted on the frame substantially co-axial with the point of oscillation.

6. In a peach pitting machine of the character described, a revolvably supported rock shaft, a carrier mounted on the rock shaft and freely adjustable in relation thereto, a rocker pivotally mounted on the carrier, and an arched blade secured at opposite ends to the rocker, and means for simultaneously rocking said shaft and said rocker.

7. In a peach pitting machine of the character described, means for pitting bisected peaches including a rock shaft, an offset on said shaft, a support thereon, an arched blade secured to a frame pivotally mounted to the support, a rotatable cam associated with the support and engaging the frame for oscillating the same on its pivot, means for oscillating the rock shaft, and means for revolving the cam.

8. In a peach pitting machine of the character described, means for pitting bisected peaches including a revolvably supported hollow shaft provided with an offset portion, an arched blade pivotally supported on the offset portion and intercepting the main axis of the shaft, driving means extending through the hollow shaft arranged for oscillating the blade on its pivotal support and means for simultaneously revolving the shaft.

9. In a peach pitting machine of the character described, means for pitting bisected peaches including a hollow shaft with an offset, an arched blade pivotally and adjustably supported on the offset, and driving means extending through the hollow shaft including universal and sliding joints arranged for oscillating the blade on its pivot and permit adjustment of the blade relative to the hollow shaft.

10. In a peach pitting machine of the

- character described, devices for holding the fruit centralized from the bloom and the stem ends, the device at the stem end being adapted to straddle a piece of stem remaining on the fruit.
11. In a peach pitting machine of the character described, devices for holding the fruit centralized from the bloom and stem ends, the device at the stem end being of hollow form to surround a piece of stem remaining on the fruit.
12. In a peach pitting machine of the character described, devices for holding the fruit centralized from the bloom and the stem ends, the device at the stem end being of tubular form adapted to contact at its end with the depression at the stem end of the fruit.
13. In a peach pitting machine of the character described, devices for holding the fruit centralized from the bloom and the stem ends, the device at the stem end being of tubular form adapted to contact at its end with the depression at the stem end of the fruit, and the contacting tubular end being transversely slotted.
14. In a peach pitting machine of the character described, a rotatable carrier, peach receiving devices thereon adapted to centralize the fruit from the stem and bloom ends, the device at the stem end being movable in the plane of rotation of the carrier from an operative to a non-operative position.
15. In a peach pitting machine of the character described, a rotatable carrier, peach receiving devices thereon adapted to centralize the fruit from the stem and bloom ends, the device at the stem end being slidably and pivotally movable from an operative to a non-operative position.
16. In a peach pitting machine of the character described, a rotatable carrier, peach receiving devices thereon adapted to centralize the fruit from the stem and bloom ends, the device at the stem end being slidably and pivotally movable in the plane of rotation of the carrier from an operative to a nonoperative position.
17. In a peach pitting machine of the character described, a rotatable carrier, devices thereon adapted to centralize a peach by impingement respectively against the stem end and the bloom end thereof, and means for lifting the device from the stem end perpendicularly from the peach and for then swinging it in the plane of rotation of the carrier.
18. In a peach pitting machine of the character described, a rotatable carrier, devices thereon adapted to centralize a peach by impingement respectively against the stem end and the bloom end thereof, and means for lifting the device from the stem end perpendicularly from the peach and for then swinging it towards the carrier, said means comprising the instrumentalities substantially as shown in the drawings hereto.
19. In a peach pitting machine of the character described, co-operating peach impaling pins mounted to be movable in an arc, said pins being formed to the arc and each having a plate-like portion adapted for securing to the mounting.
20. In a peach pitting machine of the character described, two sets of peach impaling pins, each set being mounted to move in an arc for impaling a peach between them, and each set comprising spaced pins joined by a plate adapted for clamping to the mounting.
21. In a peach pitting machine of the character described, a peach impaling device comprising a pair of spaced pins joined at one end only by a flat web all struck from a common sheet of metal.
22. In a peach pitting machine of the character described, a pitting table, means for presenting a half peach to the table and means for clamping it thereto, the clamping means comprising a stretched rubber band adapted to be forced against the half peach.
23. In a peach pitting machine of the character described, a pitting table, means for presenting a half peach to the table and means for clamping it thereto, the clamping means comprising a stretched rubber band adapted to be forced against the half peach and being relatively non-stretchable where it contacts the peach, and stretchable beyond that point.
24. In a peach pitting machine of the character described, a pitting table, means for presenting a half peach therover, and means for clamping it thereto, the first means comprising an impaling device upon which the half peach is carried, and the second means individual flexible devices at either side of the impaling device, and means for forcing the flexible devices against the half peach.
25. In a peach pitting machine of the character described, a pitting table, means for presenting a half peach to the table and means for clamping it thereto, the first means comprising a movable arm with an impaling pin projecting therefrom and on which the half peach is impaled, and the second means comprising a movable arm adjacent the first arm and having resilient means thereon at either side of the impaling pin adapted to be pressed against the half peach and force it partly from the pin and against the table.
26. In a peach pitting machine of the character described, a pitting table, means for presenting a half peach therover and means for clamping it thereto, the first means comprising a movable arm with an impaling pin projecting therefrom and on

which the half peach is impaled, and the second means comprising a movable arm adjacent the first arm and having a pair of elastic bands thereon, one to either side of the impaling pin and adapted for pressing against the fruit to force it from the pin slightly and against the table.

27. In a peach pitting machine of the character described, a pitting table, means for presenting a half peach thereover and means for clamping it thereto, the clamping means comprising two stretched rubber bands adapted to be forced against the rounded side of the half peach, one band to either side of the center of the fruit.

28. In a fruit pitter of the character described, a rotatable carrier adapted to carry the fruit past various instrumentalities for operating thereon, a lever in the path of the fruit adapted to be tripped thereby, and a counter connected therewith adapted to record the tripping of the lever.

29. In a fruit pitter of the character described, a rotatable carrier having devices thereon adapted to impinge the fruit from opposite sides and carry it past various instrumentalities for operating thereon, a lever positioned in the path of the fruit between the impinging devices adapted to be tripped by the fruit in passing, and a counter connected therewith adapted to record the tripping.

30. In a machine of the character described, a circular saw for bisecting fruit, means for carrying the fruit into engagement with and past the saw for bisecting it, a guard over the rim of the saw at the portion where the fruit leaves the same, and means for separating the halves of the fruit before passing the saw to clear the guard.

31. In a machine of the character described, a rotatable carrier, means for intermittently advancing the carrier a fraction of a revolution and means for locking the carrier at the end of each movement, said latter means comprising brackets on the carrier, and a movable arm having spaced rollers adapted to respectively engage opposite sides of the brackets.

32. In a machine of the character described, a rotatable carrier, means for intermittently advancing the carrier a fraction of a revolution, brackets on the carrier, and a movable arm having a fixed and a resilient element adapted to engage the brackets separately therebetween.

33. In a machine of the character described, a carrier rotatable around a fixed shaft, fruit receiving and centering devices projecting radially from said carrier, means for moving said devices in and out of operative positions embracing a stationary grooved face cam secured to the fixed shaft, and cam rollers associated with the devices working in the groove, said groove having

an outwardly directed opening for the radial insertion of the rollers into the groove.

34. In a machine of the character described, a rotatable carrier and a pitting mechanism, fruit holding means projecting from the carrier adapted to carry fruit over the pitting mechanism, means for intermittently actuating the carrier and the pitting mechanism, the means actuating the pitting mechanism being resiliently connected whereby the mechanism may lag or stop in its operative movement.

35. In a structure as defined in claim 34, locking means for preventing the actuation of the carrier released by the completed movement of the pitting mechanism.

36. In a machine of the character described, a revolvable shaft, a curved blade mounted thereon and adapted to swing in a curve to cut out a fruit pit, and yielding means for revolving said shaft whereby the shaft may lag upon the blade meeting an obstruction.

37. In a machine of the class described, a rock shaft, a curved blade mounted thereon and adapted to swing in a curve to cut out a fruit pit, said shaft being rocked one way by resilient means during the cutting movement, and in the opposite direction by positive means.

38. In a peach pitting machine of the character described, means for holding the fruit for operation thereon by the machine including a centralizing device adapted to impinge the stem end of the fruit and adapted to straddle a piece of stem remaining on the fruit.

39. In a machine of the character described, a rotatable carrier and a pitting mechanism for pitting fruit carried by the carrier, a source of power, transmission mechanism for alternately actuating the carrier and the pitting mechanism, a foot operated clutch for applying power to said transmission mechanism, and means for rendering the foot operated clutch inoperative during the pitting movement of the pitting mechanism.

40. In a machine of the character described, a pair of fruit impaling pins arranged in parallel spaced relation and integrally connected together at one end by a plate portion extending in the plane of the pins and adapted for securing to a mounting.

41. In a machine of the character described, a power actuated saw, means for passing fruit thereover for bisecting, and means resiliently pressed against opposite sides of the saw adapted for cleaning the same.

42. In a machine of the character described, a power actuated saw, means for passing peaches thereover for bisecting, capillary devices against the sides of the saw

and means for applying water to the capillary devices.

43. In a fruit pitting machine of the character described, a curved blade mounted to swing in an arc to cut out a fruit pit, yielding means for swinging said blade whereby the same may lag upon meeting an obstruction.

44. In a fruit pitting machine of the character described, a bowed blade forming a complete arch mounted to swing in an arcuate path on an axis substantially parallel to the plane of the arch and adapted to cut around a half pit of a half peach presented thereto, means for positioning a half peach in cutting relation to the blade, and means for resiliently urging the blade bodily toward the pit while cutting therearound.

45. In a peach pitter of the character described, a shaft with an offset, a frame mounted on the offset and guided for movement toward and from the main shaft axis, a rocker bar pivotally mounted on the frame, an arched blade secured to the rocker bar, resilient means for urging the frame toward the offset, and means for oscillating the bar.

46. In a machine of the character described, endwise opposed pins arranged to move together toward a common center to impale fruit thereon from opposite sides of the fruit and impinge endwise against the pit of the fruit for centering the same, said pins having a substantially uniform channel cross section through their operative portions.

47. In a machine of the character described, impaling devices for impaling fruit from opposite sides, means for positively moving the devices in and out of the fruit, and a resilient element interposed in said means to cushion the inward movement.

48. In a fruit pitting machine of the character described, a bowed blade forming a complete arch mounted to swing in an arc-

uate path on an axis substantially parallel to the plane of the arch and adapted to cut around a half pit of a half peach presented thereto, means for positioning a half peach in cutting relation to the blade, means for swinging the blade, and means for forcing the blade to resiliently hug the pit in cutting therearound.

49. In a structure as specified in claim 48, said blade being formed with its cutting edge in relation to its concave side that the latter will form a guard against the cutting edge striking the pit in passing therearound.

50. In a fruit pitting machine of the character described, a blade forming a complete arch, said blade being mounted on a revolvable shaft and adapted to swing in an arcuate path for cutting out a half pit from a half peach presented thereto, means for positioning a half peach in cutting relation to the blade, means for turning the shaft, and means adapting the blade to rise bodily over the pit in addition to its swinging movement with the shaft.

51. In a fruit pitting machine of the character described, a bowed blade forming an arch mounted to swing in an arcuate path on an axis substantially parallel to the plane of the arch and resiliently supported to move bodily endwise of the arch.

52. In a fruit pitting machine of the character described, a bowed blade forming an arch mounted to swing in an arcuate path on an axis substantially parallel to the plane of the arch and resiliently pivoted to tip bodily endwise of the arch.

53. In a machine of the character described, means for removing the half pits of halved fruit comprising, means for supporting the half fruit for pitting, a curved blade forming a complete arch mounted to swing in an arc and to cut out the half pit of a half fruit so supported, and means for causing the arched blade to resiliently hug the pit in swinging the blade.

JOSEPH P. BEM.
